(57) **CLAIM**

The ornamental design for a utensil handle, as shown and described.

DESCRIPTION

FIG. 1 is a perspective view of a utensil handle showing my new design;

FIG. 2 is a bottom view thereof;

FIG. 3 is a top view thereof;

FIG. 4 is a side view thereof;

FIG. 5 is a front view thereof;

FIG. 6 is a back view thereof;

FIG. 7 is a perspective view of the utensil handle in the context of being coupled with a spoon head;

FIG. 8 is a perspective view of the utensil handle in the context of being coupled with a ladle head; and,

FIG. 9 is a perspective view of the utensil handle in the context of being coupled with a spatula head.

The portions of the figures that are presented in broken lines merely illustrate the environment of the design and are not part of the claimed design.

1 Claim, 6 Drawing Sheets
